UNITED STATES PATENT OFFICE.

HUGO HEINZL, OF FISCHERN, NEAR CARLSBAD, AUSTRIA-HUNGARY.

JOINT FOR CROSSING METAL BARS.

1,083,931.

Specification of Letters Patent.

Patented Jan. 13, 1914.

Application filed March 21, 1913. Serial No. 755,858.

To all whom it may concern:

Be it known that I, HUGO HEINZL, a subject of the Emperor of Austria-Hungary, residing at Fischern, near Carlsbad, Bohemia, Austria-Hungary, have invented a new and Improved Joint for Crossing Metal Bars, of which the following is a specification.

This invention relates to a joint for crossing metal bars, by means of which the bars are rigidly connected at their point of intersection in a simple manner, without the use of rivets or other outwardly visible fastening means.

15 The invention is well adapted for fixing the joint of intersecting metal sash bars, but is equally applicable to metal bars used for other purposes.

In the accompanying drawing: Figure 1 is a perspective view of a joint for metal bars embodying my invention; Fig. 2 a side view of one of the bars; Fig. 3 a side view of the other bar; Fig. 4 a section on line 4—4, Fig. 5; Fig. 5 a plan; Fig. 6 a section 25 on line 6—6, Fig. 7; Fig. 7 a plan of a modification of the joint, and Fig. 8 a detail of the key pertaining to said modification.

One of the two metal bars, rails or similar members *d* to be connected, is provided 30 at the point of intersection with an upper transverse slot *e* which opens at its lower end into a longitudinal slot *a*. The second member *d* is provided at its point of intersection with a lower transverse slot *f*, which 35 opens at its upper end into a longitudinal slot *a'*. The two members thus constructed, are made to straddle each other, so that in this way, the upper edges as well as their lower edges will be placed in like horizontal 40 planes, while the longitudinal slots *a*, *a'* will become horizontally alined to jointly form a cruciform pocket. Into this pocket, there is fitted a key *b*, which is preferably made 45 in the form of a disk, and which is of a size and thickness to snugly engage slots *a*, *a'*. In order to introduce this key, slot *a* is laterally extended at one end, and there is provided on the member *d* having said slot, an integral tongue *c* that extends into the 50 prolonged part of the slot. Tongue *c* is

prior to the assemblage of the parts, bent sidewise (Fig. 5) and after the key has been seated, it is again bent back into its normal position to thus lock the key in place.

With the construction shown in Figs. 55 6-8, the slot *a* is likewise extended along one end, but the tongue *c* is omitted. In lieu thereof, a tongue *b'* is formed on the key *b'*, which, after the introduction of the key is secured to the corresponding member 60 *d* by upsetting its edges against opposite faces of said member or in other suitable manner.

I claim:

1. A joint of the class described, comprising a pair of straddling bars having transverse slots and longitudinal slots at the ends of the transverse slots, said longitudinal slots forming jointly a pocket, a locking member positioned entirely within said 65 pocket and bounded and maintained in position by said bars at the ends of the pocket-forming slots, and means for securing said locking member within said pocket.

2. A joint of the class described, comprising a pair of straddling members, each member being provided with a transverse slot and with a longitudinal slot, a disk-shaped key engaging the longitudinal slots of both members, one of the longitudinal slots being 70 extended for the introduction of said key, and means for locking the key within the longitudinal slots.

3. A joint of the class described, comprising a pair of straddling members, each member being provided with a transverse slot and with a longitudinal slot opening into the transverse slot, one of the longitudinal slots having an extension, a key engaging the longitudinal slots of both members, and a 85 tongue integral with one of said parts and projecting into the longitudinal slot extension.

In testimony whereof I affix my signature in presence of two witnesses.

HUGO HEINZL.
